UNITED STATES PATENT OFFICE.

AUGUST J. HARTFIELD, OF LOS ANGELES, CALIFORNIA, ASSIGNOR TO HELEN A. HARTFIELD, OF LOS ANGELES, CALIFORNIA.

GAS HEAT-RADIATOR.

1,229,451.

Specification of Letters Patent. Patented June 12, 1917.

Application filed July 8, 1916. Serial No. 108,099.

To all whom it may concern:

Be it known that I, AUGUST J. HARTFIELD, a citizen of the United States of America, residing at Los Angeles, county of Los Angeles, State of California, have invented a certain new and useful Gas Heat-Radiator; and I do hereby declare the following to be a full, clear, and exact description of the invention, such as will enable others 10 skilled in the art to which it appertains to make and use the same.

This invention relates to improvements in gas heat radiators; more particularly to improvements in the construction disclosed in 15 my Patent No. 1,181,382, dated May 2, 1916.

One object of the invention is to provide in the combustion chamber a flue which is so formed and arranged that when the burner is lighted the air in said flue is 20 quickly heated and consequently rarefied so that it moves out of the flue and thus facilitates the movement of the products of combustion from the combustion chamber to the outlet of the radiator.

25 Further objects of the invention are to provide a novel and improved gas heat radiator which is highly practical and serviceable, clean and odorless in operation; economical, convenient, and sanitary in use, 30 and efficient in action.

Other objects and the advantages of the invention will be apparent to those skilled in the art from a careful consideration of the following description of the preferred 35 construction embodying the invention, taken in connection with the accompanying drawings in which—

Figure 1 is a front elevational view of the improved gas heat radiator; Fig. 2 is a sectional view taken on the line 2—2 of Fig. 40 1; Fig. 3 is a broken sectional view taken on the line 3—3 of Fig. 2; Fig. 4 is a broken side view of the lower part of the combustion chamber; and Fig. 5 is an elevational 45 view of the hood.

As shown in the drawings, the central burner section or combustion chamber 7 is provided in the upper and lower parts thereof with side openings or ports 8 into which 50 latter are fitted the nipples 9 whereby the combustion chamber 7 is connected to a plurality of radiator sections 10 which are disposed on each side of the combustion chamber 7 and are connected by the nipples 55 9 fitted in the usual ports which are pro-

vided in the upper and lower parts of the radiator sections 10.

Within the lower part of the combustion chamber 7 is arranged the burner 11 to which is connected one end of the pipe 12 60 which passes through an opening 13 in one side of the combustion chamber 7 and has on its other end the flaring fitting 14 into which extends the gas fuel supply piping 15 which latter is provided with the regulating valve 16 and the admission valve 17.

The combustion chamber 7 is provided in the interior thereof with a ledge 18 on which rests the flaring lower end portion 19 of the baffle plate or hood 20, which latter is 70 open only at its upper and lower ends and surrounds the upper part of the burner 11 and has its converging upper end portion 21 extending above the burner 11, as shown. Opposite to the hood 20, the combustion 75 chamber 7 is provided with openings or vents 22. The passageways 11' in the upper part of the burner 11 preferably extend substantially parallel to the inner wall of the hood 20 so that the gas flame is directed 80 away from the inner wall of the hood and toward the opening in the top end of the hood. To permit access to the burner 11 and the placing of the hood 20 on the ledge 18, a door 23 is provided at the lower front 85 part of the combustion chamber 7.

The combustion chamber 7 is provided with the waste gas flue 24 which is in communication with the ports 8 in the lower part of the combustion chamber 7 and extends upwardly above the burner 11 and as shown is so formed and arranged that when the burner 11 is lighted the air in said flue is quickly heated and rarefied so that it moves out of said flue and thus causes a 95 quick movement of the products of combustion or waste gas from the combustion chamber 7 to the outlet 25 of the radiator. In this instance the partition wall 26 divides the central burner section 7 into the combustion chamber and the waste gas offtake flue 24. The central burner section 7 is provided with an air inlet port 27 in its lower part below the burner 11. A pipe or duct 28 is connected to the outlet 25 and 100 adapted to carry off the products of combustion from the flue 24 to the outside of the building in which the radiator is installed.

From the foregoing description the oper- 110

ation and advantages of the improved gas heat radiator will be apparent to those skilled in the art. When the burner 11 is lighted the air in the flue 24 is quickly heated and rarefied and its back pressure is so reduced as to cause a quick movement of the products of combustion from the combustion chamber 7 to the outlet 25. The heated products of combustion pass from 5 the burner 11 to the upper part of the combustion chamber 7 and thence pass downwardly through the sections 10 and thence through the flue 24 to the outlet 25 and pipe 28. When starting to operate the gas 10 heat radiator the latter is filled with cold still air which causes a back pressure and consequently a choking effect on the flame of the burner 11, but the vents 22 permit the egress of a portion of the cold air so that 15 the heated products of combustion are enabled to quickly force their way through the radiator and remove the still air. When the radiator is in full operation some air is drawn into the radiator through the vents 20 22. The hood or baffle plate 20 shields the burner 11 from back drafts due to gusts of wind by deflecting the back drafts through the vents 22 and thus it prevents putting out of the fire in the combustion 25 chamber 7.

The construction which has been particu-

larly illustrated and described admits of minor changes and modifications, wherefore the right is reserved to all such changes and modifications as do not depart from the spirit and scope of the invention which is defined in the appended claim.

I claim:

A ventilating gas heat radiator comprising a central burner section having a partition wall dividing the same into a combustion chamber and a waste gas offtake flue, a gas burner disposed in the lower part of the combustion chamber, a baffle plate arranged above said burner and provided with 40 upwardly converging walls and having an open top, said central burner section having an air inlet port below said burner and having auxiliary air inlet ports opposite the baffle plate, a plurality of radiator sections arranged at the sides of the central burner section and connected so that at their 45 upper parts they are in open communication with the upper part of said combustion chamber and at their lower parts they are in open communication with said waste gas offtake flue.

In testimony whereof, I have signed my name to this specification at Los Angeles, county of Los Angeles, State of California, 50 this 30th day of June A. D. 1916.

AUGUST J. HARTFIELD.
